US00D627855S

(12) **United States Design Patent**
Ito

(10) **Patent No.:** **US D627,855 S**
(45) **Date of Patent:** **** Nov. 23, 2010**

(54) **CONSTANT TEMPERATURE LIQUID CIRCULATING DEVICE**

(75) Inventor: **Noriaki Ito**, Tsukubamirai (JP)

(73) Assignee: **SMC Corporation**, Chiyoda-ku, Tokyo (JP)

(**) Term: **14 Years**

(21) Appl. No.: **29/334,349**

(22) Filed: **Mar. 25, 2009**

(30) **Foreign Application Priority Data**

Oct. 23, 2008 (JP) 2008-027259

(51) **LOC (9) Cl.** **23-01**

(52) **U.S. Cl.** **D23/200**

(58) **Field of Classification Search** D23/200, D23/213, 225; 210/195.2, 295, 296
See application file for complete search history.

(57) **CLAIM**

The ornamental design for a constant temperature liquid circulating device, as shown and described.

DESCRIPTION

FIG. 1 shows a front view of a constant temperature liquid circulating device showing my new design;

FIG. 2 shows a rear view thereof;

FIG. 3 shows a right side view thereof;

FIG. 4 shows a left side view thereof;

FIG. 5 shows a top view thereof;

FIG. 6 shows a bottom view thereof;

FIG. 7 shows a top, front and left side perspective view thereof; and,

FIG. 8 shows a top, bottom, rear and right side perspective view thereof.
